UNITED STATES PATENT OFFICE.

CHRISTIAN WILLIAM MEINECKE, OF JERSEY CITY, NEW JERSEY, ASSIGNOR TO WHITALL TATUM COMPANY, OF NEW YORK, N. Y., A CORPORATION OF NEW JERSEY.

DESIGN FOR AN ATOMIZER.

No. 39,054.

Specification for Design.

Patented Feb. 4, 1908.

Application filed October 2, 1906. Serial No. 337,131. Term of patent 14 years.

To all whom it may concern:

Be it known that I, CHRISTIAN WILLIAM MEINECKE, a citizen of the United States, residing at Jersey City, in the county of Hudson and State of New Jersey, have invented a new, original, and ornamental Design for Atomizer-Nozzles, of which the following is a specification, reference being had to the accompanying drawing, forming a part thereof.

The figure is a perspective view of an atomizer nozzle, showing my new design.

I claim:

The ornamental design for an atomizer nozzle, as shown.

CHRISTIAN WILLIAM MEINECKE.
